UNITED STATES PATENT OFFICE.

LOUIS H. NEALY, OF NEWARK, NEW JERSEY.

PICTURE-WIRE FASTENER.

SPECIFICATION forming part of Letters Patent No. 550,456, dated November 26, 1895.

Application filed April 5, 1895. Serial No. 544,539. (No model.)

To all whom it may concern:

Be it known that I, LOUIS H. NEALY, a citizen of the United States, residing at Newark, in the county of Essex and State of New Jersey, have invented certain new and useful Improvements in Picture-Wire Fasteners; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to improvements in picture-wire fasteners, and has for its object to provide a device to be used in connection with the screw-eyes on the back of a picture or other frame, to which the picture-wire can be secured without twisting or tying, as is now the case.

The invention therefore consists in the novel construction of a picture-wire fastener as an article of manufacture, and also in the novel arrangements and combinations of parts to be hereinafter fully described, and finally embodied in the clauses of the claim.

In the accompanying sheet of drawings is illustrated the nature of my invention, which is designed to make a simple, strong, and practical construction for which the fastener is designed.

In the several views, Figure 1 is a view of the back of a frame provided with the ordinary screw-eyes to which the attachments or fasteners embodying the principles of my invention have been secured. Fig. 2 is a top view of the screw-eye and the picture-wire fastener, and Fig. 3 is a back view of the same.

Fig. 4 is a longitudinal vertical section of the screw-eye and attachment, with the end of the picture-wire held in position by said fastener. Fig. 5 is a perspective view of the picture-wire fastener, and Fig. 6 is a plan view of a fastener of a slightly modified form of construction.

Similar letters of reference are employed in each of the above-described views to indicate corresponding parts.

In said drawings, *b* indicates the usual form of screw-eye, which is secured into the

back of a picture or other like frame by means of the screw end *b'*.

My novel form of picture-wire fastener consists, essentially, of a plate *a*, made of spring metal, which is circular in outline and is approximately of the same diameter as the largest diameter of the ring of the screw-eye *b*. At one end of said plate *a* is a lip *a'*, provided with a hole or perforation *a²*, through which the screw *b'* of the screw-eye *b* is passed, and when firmly screwed into the frame said lip *a'* of the plate *a* forms a bearing to securely bring the upper surface of said plate *a* in close contact with the under portion of the ring or eye portion of the screw-eye *b*, as will be clearly evident from an inspection of Figs. 1 and 4. Said plate is formed with a holding-tongue *a³*, struck up therein by means of a suitable die, and is provided with the curved portion *a⁴*, as clearly shown in Fig. 5. Said tongue extends from side to side of said plate *a* in a line which is approximately parallel to said lip *a'*, as will be seen from Figs. 2 and 3, and to one side of the plate *a*, in a straight line *a⁵*, with said raised portion *a⁴* is a perforation or hole *a⁵*, as shown in Fig. 5, or an opening *a⁶*, of the shape illustrated in Fig. 6. The end of said tongue *a³* is slightly curved upwardly to form a suitable finger-piece or lift *a⁷*, as will be clearly evident. In order to apply the fastener to the picture-wire to avoid the twisting or tying of the ends, as is now the custom, the end portion *c* of the wire is passed through the ring or eye of the screw-eye *b* and then through the perforation or hole *a⁵* or the opening *a⁶* in the plate *a* and finally between the space formed by the under surface *a⁸* of the plate *a* and the raised portion *a⁴* of the tongue *a³*.

The weight of the frame will draw the plate *a* firmly against the eye or ring of the screw-eye *b*, and the wire *c* will be securely held or clamped by the friction between the wire and the parts of the plate and the ring of the screw-eye, through which the wire is passed, as will be evident, without necessitating the twisting or tying of a knot in the wire.

By slightly raising the tongue *a³* by means of its finger-piece or lift *a⁷* the wire can be readily drawn through the hole *a⁵* or the opening *a⁶* in the plate *a* to adjust the hanging

distance of the frame against the wall, and when thus adjusted the tongue a^3 is again made to bind with and against the wire, thereby safely retaining the frame in its adjusted 5 position against the wall.

By this means it will be seen that I have devised a simple and operative fastener to be used in connection with a screw-eye for readily adjusting the hanging distance of a 10 frame against the wall and at the same time avoiding the twisting or tying of a knot in the wire.

Having thus described my invention, what claim is—

15 1. The combination, with a screw-eye having a screw b' , of a picture-wire fastener, consisting essentially, of a plate a having a lip a' and a perforation in said lip, through which

said screw b' is passed, and a spring tongue a^3 on said plate, substantially as and for the 20 purposes set forth.

2. The combination, with a screw-eye having a screw b' , of a picture-wire fastener, consisting essentially, of a plate a having a lip a' and a perforation in said lip, through which 25 said screw b' is passed, a spring tongue a^3 , and a perforation or other similar opening in the body of said plate, substantially as and for the purposes set forth.

In testimony that I claim the invention set 30 forth above I have hereunto set my hand this 4th day of April, 1895.

LOUIS H. NEALY.
